UNITED STATES PATENT OFFICE.

HAAKON A. MARTIN, OF DAYTON, OHIO, ASSIGNOR TO THE NATIONAL CASH REGISTER COMPANY, OF DAYTON, OHIO, A CORPORATION OF OHIO, (INCORPORATED IN 1906.)

ALARM AND LOCK-CONTROL FOR CASH-REGISTERS.

1,136,152.

Specification of Letters Patent. Patented Apr. 20, 1915.

Application filed June 27, 1913. Serial No. 776,036.

To all whom it may concern:

Be it known that I, HAAKON A. MARTIN, a citizen of the United States, residing at Dayton, in the county of Montgomery and State of Ohio, have invented certain new and useful Improvements in Alarm and Lock-Control for Cash-Registers, of which I declare the following to be a full, clear, and exact description.

This invention relates to improvements in cash registers of the type having a plurality of drawers released by operations of the machine and having independent alarms of different tones arranged so that when a drawer is opened its alarm will be sounded.

One object of this invention is to provide simple and effective interlocking devices between the cash drawers and the drawer controlling mechanism for preventing, when desired, successive operations involving the same drawer while the drawer remains open, but at the same time permitting operations of the register to enter transactions involving other drawers. In the following description this interlocking mechanism is spoken of as the key lock mechanism, owing to the fact that the effect of its operation is to prevent depressing the key corresponding to a particular drawer while the drawer remains open.

Another object is to provide a simple means for disabling the key lock mechanism when it is desired to make successive operations involving the same drawer with the drawer open.

Still another object is to provide a single lock controlled device which may be adjusted to various positions to disable the key lock mechanism only or to simultaneously disable both the key lock mechanism and the alarm sounding mechanism.

With these and incidental objects in view, the invention consists in certain novel features of construction and combinations of parts the essential elements of which are set forth in appended claims, and a preferred form of embodiment of which is hereinafter described with reference to the drawings which accompany and form part of this specification. Of said drawings: Figure 1 is a sectional view through the machine showing the drawer controlling mechanism with

parts of the improvement assembled in position. Fig. 2 is a rear view showing the drawer releasing mechanism and the related parts of the improvement. Fig. 3 is an enlarged detail view of a part of the key lock controlling devices. Fig. 4 is a plan view of the drawer releasing mechanism showing the construction and application of the improvement. Fig. 5 is an enlarged detail showing a section of the improvement. Fig. 6 is a detail perspective view of one of the bell hammers and mechanism associated therewith.

The invention is shown embodied in a register of the general type disclosed in United States Letters Patent No. 616,866, granted December 27th, 1898, to W. F. Bockhoff. Only two drawers and two initial keys are shown. Instead of the differential mechanism controlling the positioning of the drawer releasing mechanism as shown in the Bockhoff patent the present construction has mechanism between the keys and the drawer releasing element proper whereby pressing one of the keys in will positively position the common drawer releasing element so that when the register is operated the drawer represented by the key pressed will be opened. This positive mechanism is shown and described in the pending application No. 665,086 filed by E. J. Von Pein, December 11th, 1911. The register also contains drawer latching mechanism, latch tripping devices, bell sounding devices and bell muffler mechanism disclosed in United States Letters Patent No. 745,937, to E. J. Von Pein, dated Jan. 5, 1901. Reference may be had to the patents and application mentioned for a complete description of the illustrative machine.

The improvement made by this invention to the previous mechanism consists mainly in providing an improved key lock mechanism by which successive operations of the machine involving the same drawer may be prevented without interfering with operations of the register to make entries involving the other drawer. A controlling device is provided whereby this key lock mechanism may be disabled when it is desired to operate the register repeatedly with the drawers open. The bell muffler mechanism

described in the Von Pein patent has a device for disabling the bell sounding devices and part of the present invention consists in combining in one lock controlled 5 manipulative device means for disabling the key lock only or simultaneously disabling both the key lock and the bell ringing mechanism according to the position to which the manipulative device is adjusted.

10 As shown in the patents and application referred to, the machine is provided with banks of keys of which only one bank is shown in the accompanying drawings. This bank contains two initial keys 1 and 2 arranged to be pressed in against the tension of their springs and locked in the depressed position by the detent 3 and the retaining bar 4 in a manner fully explained in the Bockhoff patent. Each of the keys carries 15 a pin 5 for holding the spring in position and extending at right angles to the shaft of the key into the path of one or the other of the slides 6 and 7. These slides are provided with slots at their ends, the upper slots spanning a stub shaft 8 fastened in the key bank frame, while the lower slots span the shaft 9 running through the frames of the machine. The slots are so arranged that the slides are allowed a certain extent of 20 longitudinal movement. The slides are connected by links 10 and 11 to arms 12 and 13 secured to a rock shaft 14. It will be seen that when a key 1 is pressed in the shaft 14 will be rocked anti-clockwise and the slide 25 7 moved toward the front of the machine, while pressing the key 2 reverses this operation. Fastened to the shaft 14 is a bevel gear 15 (Fig. 2) which is always in mesh with the bevel gear 16. This gear 16 has a 30 feather and groove connection with the drawer releasing rod 17 so that when the gear is turned the rod will be rotated but at the same time the rod is free to be moved vertically.

35 40 45 Fastened to the lower end of the rod 17 is an arm 18 with two upwardly extending projections 19. Depressing the keys 1 and 2 in succession will, through the mechanism just described, turn the rod 17 first 50 in one direction and then the other thus bringing the projections 19 alternately under their corresponding levers 20. Each drawer is provided with a spring operated latch 21 which engages a latch plate 22 fastened to the machine frame and holds the 55 drawer closed and for each latch there is one of the levers 20. These levers are pivoted as at 23 to one of the frames of the machine with one end extending above the 60 rear end of the latch 21 and the other arranged to be engaged by the corresponding projection 19 on the operating arm when the rod 17 is raised. The mechanism for lifting the rod 17 comprises a lever 27 (Fig. 65 2) pivoted at 28 and extending across the

rear of the machine under a collar 24 fastened to the rod 17, a pitman 29 and a cam 31 fastened to the shaft 30. The upper end 70 of the pitman has a hook shaped extension engaging the shaft 30, which is one of the main driving shafts of the register and given a complete rotation on every operation of the machine, while the lower end of the pitman engages and supports the free end of the lever 27. A stud 32 at the upper 75 end of the pitman rides on the face of the cam 31 so that every time the register is operated and the shaft 30 rotated the pitman is lifted and the end to which it is attached to the lever 27 is raised. As stated 80 before, the collar 24 under which the lever passes is secured to the rod 17 so when the lever 27 is raised as just described the rod is lifted and the spring 251 compressed between the collar 24 and the bracket 26. 85 This causes which ever projection 19 is at the time positioned under one of the levers 20 to turn such lever on its pivot and disengage the corresponding catch 21 from the plate 22. The drawer is then free to be 90 ejected by a spring 65 or opened in any other manner desired. This mechanism also operates the bell ringing mechanism. For each of the bells 33 there is provided a bell hammer 34 pivoted at 35 with an extension 36 to engage the stop stud 37. The hammer is always under the tension of the spring 38. Pivoted at 40 to the lever 20 is a pawl 39 having an extension at the upper 95 end engaging a corresponding extension on the bell hammer. A spring 41 at all times urges the pawl 39 toward the bell hammer 34. When the lever 20 is operated by the drawer release arm 18 as above described, the pawl 39 will rotate the bell hammer on 100 its pivot until the projection on the pawl trips off the projection on the bell hammer 34, allowing the spring 38 to snap the hammer against the bell and make an alarm. When the lever 20 is drawn back toward 110 normal position by the spring 41 the pawl 39 will pass along the edge of the bell hammer until the two projections again come into engagement as shown in Fig. 2.

115 It will readily be understood from the description in the foregoing that when a key is pressed in and the arm 18 positioned, the arm is held rigid, as the key depressed is locked in the depressed position with the pin resting against the end of its corresponding slide 6 or 7, but as soon as the key is released during the operation of the machine there is nothing to prevent the arm 18 from being swung from side to side, as the rod 17, shaft 14, and the slides 6 and 7 are all free to be moved in either direction, to the limit of their respective extents of movement.

120 The key lock mechanism of this invention consists of a device for each drawer 125

which automatically pushes the arm 18 out of engagement with the lever 20 as soon as the drawer is opened, and then prevents the arm 18 from being again brought into operative relation with the same lever 20 until the drawer is closed. When the arm 18 is swung and held in this manner the result is that the slide 6 or 7 for the open drawer is carried forward and held in the forward position so that the corresponding key cannot be pushed in far enough to be locked in by the detent 3 and retaining bar 4. The devices for swinging the arm 18 to the inoperative position consists of the arms 45 (Figs. 4 and 5) and the spring 25 which has its ends attached to studs 47 in the arms. These arms are held back out of engagement while the drawers 42 are closed by notches in the rear ends of angle irons 43 attached to the bottoms of the drawers engaging pins 44 on the arms. As these arms 45 are loosely mounted on the shafts 46, as soon as a drawer is opened and the angle iron 43 carried out of contact with the pin 44 the spring 25 will rotate the arm toward the front of the machine. Each arm carries an anti-friction roll 49 which engages one of the bevels 50 at the rear end of the releasing arm 18 and, as at the beginning of the operation the arm 18 is locked in position under the lever 20, the roll 49 is stopped against the bevel. However, as soon as the key is released and the arm left free to move as before described, the spring 25 will cause the arm 45 and roller 49 to act against the beveled end of the arm 18 and cam the arm to one side so that the extension 19 will no longer be in operative relation to the lever 20. The roll then passes off of the bevel and continues toward the front of the machine until it is resting against the square side 51 of the arm 18. Consequently the arm cannot be again turned in that direction to the position where it can release the same drawer and the key corresponding to that drawer is locked against operation. When the drawer is closed the angle iron 43 engages the pin 44 and carries the arm 45 back to the normal position after which the key can again be depressed and the register operated to open the same drawer. As can be seen in Fig. 4, the width of the arm 18 and the locations of the rolls 49 on the arms 45 are such that when one of the drawers is opened the register can be operated to open the other drawer. However, the operation of the arm 45 for the second drawer will occur then as just described in connection with the first arm and as a result the arm 18 will be locked in an intermediate position, making both of the keys 1 and 2 inoperative.

In the Von Pein patent mentioned a complete description is given of the mechanism used in the present invention for disabling

the bell ringing mechanism. This disabling mechanism is usually spoken of as the bell muffling mechanism and this is the term used in the following. By a few changes and additions made to Von Pein's bell muffling mechanism, the present construction in addition to muffling the bells will also disable the key lock mechanism when it is desired to be able to make successive operations involving the same drawer with the drawer open. The bell muffler mechanism comprises two vertical shafts 46. Each shaft has a crank 52 at the upper end with a link 53 connecting the cranks in such a manner that rotation of one will rotate the other in the same direction and to the same extent. At the upper end of one of the shafts is another crank 54. Near the front of the machine is a handle 55 fastened to the upper end of a shaft which carries at its lower end the cam 56. This handle is adjustable to three positions as indicated in Fig. 4 and after being adjusted to the desired position it is locked in that position by means of a lock 57. A stub 58 has fastened to it an arm 59 which works against the cam 56. The same shaft also carries an arm 60. Attached to the arm 60 is one end of a long link 610 the other end being attached to the above mentioned crank 54. It will readily be seen that when the lock 57 is unlocked and the handle 55 turned anti-clockwise the cam 56 acting against the arm 59 will rock the stub shaft 58 and the arm 60 clockwise, forcing the link 610 toward the rear and turning the shaft 46 also in a clockwise direction. This movement is transmitted to the other shaft 46 by the intervening link 53 as before stated. Each of the shafts carries secured thereto an arm 64 (Figs. 2, 4 and 6) which when the shafts are rocked the proper distance, engages the bevel face of the lug 63 on the bell hammer trip pawl 39 and rocks the pawl on its pivot far enough to disconnect it from the bell hammer 34. Then when the lever 20 is operated as above described the bell hammer will not be affected by the pawl and the alarm will not be sounded.

Fastened to the lower ends of the shafts 46 are the short arms 61, Figs. 2, 3 and 5, carrying studs 62 which act as stops for the key lock arms 45. The radial position of the arm 61 on the shaft 46 with reference to the other parts carried by the shaft is indicated by the dotted outline in Fig. 5. When the handle 55 is at the position shown in Fig. 4, the arms 61 are held far enough toward the front of the machine for the studs 62 to permit the key lock arms 45 to rotate the distance necessary to engage the drawer releasing arm 18 and swing it to the inoperative position and lock it there. The position of the arm 61 at this time is

shown in Fig. 3. When the lever 55 is turned to the "Bell on Key-lock off" position the shafts 46 are turned and the arms 61 are carried rearwardly far enough for the studs 62 to support the arms 45 in the position in which they are normally held by the drawer angle irons 43. This position of the arm 61 and the stud 62 is indicated by the dotted outline 70, Fig. 3. It will be seen that with the arms 61 in this position the key lock arms 45 cannot swing into engagement with the arm 18 when angle iron 43 is carried out of engagement with the pin 44, so the release arm 18 remains in the position to which it was moved by one of the keys until the other key is used. There is, therefore, nothing to prevent making successive registrations with a drawer open. On turning the handle 55 to the third position, that is, the "bell off key-lock off" position, the shafts 46 are rotated still farther and the arms 61 carried to the position indicated by the numeral 71 (Fig. 3). When turned to this position the stud 62 engages the key lock arm 45, swings it toward the rear of the machine and holds it in the position shown by the dotted outline indicated by the numeral 45^a. When in this position the arm 45 is not only prevented from interfering with the position of the lever 18, but the bell muffler arms 64 are forced into engagement with the beveled lugs 63 on the bell muffler trip pawls 39. As a result the pawls 39 are cammed back out of engagement with the bell hammers, thereby disabling the bell ringing mechanism.

While the form of mechanism herein shown and described is admirably adapted to fulfil the objects primarily stated, it is to be understood that it is not intended to confine the invention to the one form of embodiment shown and described herein, as it is susceptible of embodiment in various forms, all coming within the scope of the claims which follow.

What is claimed is:

1. In a machine of the class described, the combination with an operating mechanism, of a series of independent cash drawers, independent alarms for the respective cash drawers, means requiring an operation of the operating mechanism for opening any desired drawer and sounding its alarm, means normally preventing successive operations of the operating mechanism to sound the same alarm while the drawer remains open, and a lock controlled manipulative device whereby said preventing means and all of the aforesaid alarms may be simultaneously disabled.

2. In a machine of the class described, the combination with an operating mechanism, of a plurality of separate receptacles, independent alarms for the respective recep-

70 tacles, manipulative devices under the control of which any desired receptacle may be exposed and its alarm sounded by an operation of said operating mechanism, devices controlled by the exposed receptacle locking its corresponding manipulative device against operation until the receptacle is closed, and a common means whereby the locking devices and all of the aforesaid alarms may be simultaneously disabled.

3. In a machine of the class described, the combination with an operating mechanism therefor, of a plurality of normally inaccessible receptacles, manipulative devices, means controlled by said manipulative devices and requiring an operation of the operating mechanism whereby any desired receptacle may be rendered accessible, and means comprising a plurality of spring operated arms for preventing successive operations of a manipulative device while its respective drawer remains open.

4. In a machine of the class described, the combination with an operating mechanism, of a plurality of drawers, an independent alarm for each drawer, manipulative devices, means controlled by said manipulative devices and requiring an operation of the operating mechanism for opening any desired drawer and sounding its alarm, means normally locking a manipulative device against operation while its respective drawer remains open, and an adjustable device whereby said locking means only may be disabled or both the locking means and aforesaid alarms simultaneously disabled.

5. In a machine of the class described, the combination with an operating mechanism, of a plurality of drawers, an independent alarm for each drawer, manipulative devices, means controlled by said manipulative devices and requiring an operation of the operating mechanism for opening any desired drawer and sounding its alarm, means normally locking a manipulative device against operation while its corresponding drawer remains open, and a common manipulative means whereby said locking means and all of the aforesaid alarms may be simultaneously disabled.

6. In a machine of the class described, the combination with an operating mechanism, of a plurality of drawers, an independent alarm for each drawer, means requiring an operation of the operating mechanism for opening any desired drawer and sounding its alarm, means normally preventing successive operation of the operating mechanism to sound the same alarm while the drawer remains open, and a lock controlled means whereby said preventing means only may be disabled, or both the preventing means and all of the aforesaid alarms simultaneously disabled.

7. In a machine of the class described,

75

80

85

90

95

100

105

the combination with an operating mechanism therefor, of a plurality of normally inaccessible receptacles, manipulative devices, means controlled by said manipulative devices and requiring an operation of the operating mechanism whereby any desired receptacle may be rendered accessible, means comprising a plurality of spring operated arms for preventing successive operations 10 of a manipulative device while its respective drawer remains open, and an adjustable device for holding said arms out of their effective positions when it is desired to operate a manipulative device successively with its 15 corresponding drawer open.

8. In a machine of the class described, the combination with an operating mechanism therefor, of a plurality of drawers each having a latch for holding it closed, manipulative devices, a latch tripping element positioned by any one of said manipulative devices to release its corresponding drawer when the operating mechanism is operated, and means rendered effective by the opening 25 of the drawer for automatically moving the latch tripping element out of position to release said drawer and preventing its return to the same releasing position while the drawer remains open.

30 9. In a machine of the class described, the combination with an operating mechanism therefor, of a plurality of drawers each having a latch for holding it closed, manipulative devices a latch tripping element positioned by any one of said manipulative devices to release its corresponding drawer when the operating mechanism is operated, and means rendered effective by the opening 35 of the drawer for automatically moving the latch tripping element out of the position when said drawer is released and locking the manipulative device corresponding to the open drawer against operation until the 40 drawer is again closed.

45 10. In a machine of the class described, the combination with an operating mechanism therefor, of a plurality of drawers, a common releasing device for the drawers, said releasing device being normally in an ineffective position, manipulative means for positioning the common releasing device to release any desired drawer on an operation of the operating mechanism, and means rendered effective by the opening of the drawer 50 for restoring the common releasing device to its normally ineffective position.

11. In a machine of the class described, the combination with an operating mechanism therefor, of a plurality of drawers, a 60 common releasing device for the drawers, said releasing device being normally in an ineffective position, manipulative means for positioning the common releasing device to release any desired drawer on an operation 65 of the operating mechanism, and devices

comprising a spring released when the drawer opens for restoring the common releasing device to its normal position.

12. In a machine of the class described, the combination with an operating mechanism therefor, of a plurality of drawers, common releasing devices for the drawers, said releasing devices being normally in a neutral position, manipulative devices for positioning said common releasing devices 70 to release any desired drawer by an operation of the operating mechanism, and means rendered effective by said operation for returning the common releasing devices to neutral position.

80 13. In a machine of the class described, the combination with an operating means therefor, of a plurality of drawers, a common releasing device for the drawers, said releasing device being normally in an ineffective position, manipulative means for positioning the common releasing device to release any desired drawer on an operation of the operating mechanism, devices controlled by the drawer for restoring the common releasing device to its normal position, and a manipulative device for disabling said 85 restoring means.

90 14. In a machine of the class described, the combination with a plurality of drawers, of a common drawer releasing element, manipulative devices for positively positioning said drawer releasing element to release any desired drawer, means locking the manipulative devices against operation while their 95 corresponding drawers remain open, an independent alarm for each drawer, means for sounding the alarm when a drawer is opened, and a single manipulative device controlling both the alarm sounding means and the 100 aforesaid locking means.

105 15. In a machine of the class described, the combination with a plurality of cash drawers, of a latch for each drawer, a releasing device common to all of the latches, 110 manipulative means for positioning said device in operative relationship to any desired latch means for operating said device, to trip the latch in operative relationship thereto, means for opening the drawers 115 when unlatched, and means whereby opening a cash drawer will move the releasing device out of operative relationship to the latch and hold it out while the drawer is open.

120 16. In a machine of the class described, the combination with a plurality of cash drawers, of a latch for each drawer, a shaft, means carried by the shaft for tripping the drawer latches, a manipulative device for 125 each drawer, connections whereby operation of a manipulative device will rotate the shaft to position the tripping means in operative relation to the latch of the corresponding drawer, means for operating the shaft to 130

6
trip the drawer latch, means for opening the drawer when unlatched, and means rendered effective by the opening of the drawer for reversely rotating the shaft thereby setting the aforesaid connections to lock the manipulative device against manipulation until the drawer is closed.

In testimony whereof I affix my signature in the presence of two witnesses.

HAAKON A. MARTIN.
